(57) CLAIM

The ornamental design for a portion of a shoe upper, as shown and described.

DESCRIPTION

FIG. 1 is a front perspective view of a portion of a shoe upper showing my new design.

FIG. 2 is a side view thereof.

FIG. 3 is a front view thereof.

FIG. 4 is a top view thereof; and,

FIG. 5 is a rear perspective view thereof.

The uneven broken lines immediately adjacent to the shaded area represent unclaimed boundaries of the design. The broken line circles within the shaded area represent unclaimed holes. The uneven broken line showing of the remainder of the shoe is for illustrative purposes only and forms no part of the claimed design.
